US00D657334S

(12) **United States Design Patent**
Choi

(10) **Patent No.:** **US D657,334 S**
(45) **Date of Patent:** **** Apr. 10, 2012**

(54) **MOBILE PHONE**

(75) Inventor: **Jung-Hyun Choi**, Seoul (KR)

(73) Assignee: **Samsung Electronics Co., Ltd. (KR)**

(**) Term: **14 Years**

(21) Appl. No.: **29/390,815**

(22) Filed: **Apr. 29, 2011**

(30) **Foreign Application Priority Data**

Mar. 9, 2011 (KR) 30-2011-0009494

(51) **LOC (9) Cl.** **14-03**

(52) **U.S. Cl.** ..... **D14/138 G**

(58) **Field of Classification Search** ..... D14/138 AD,
D14/138 G, 138 R, 138 AC, 138 C, 496,
D14/341, 345, 346, 203.7, 247, 248, 218,
D14/138 AA, 138 AB; 455/575.1, 556.2,
455/556.1, 575.4, 566; D10/65; D13/168
